UNITED STATES PATENT OFFICE.

JAMES C. HURD, OF SPRINGFIELD, MASSACHUSETTS, ASSIGNOR OF ONE-HALF TO JOHN E. STANNARD, OF SAME PLACE.

PAPER BOX.

SPECIFICATION forming part of Letters Patent No. 298,384, dated May 13, 1884.

Application filed February 28, 1884. (No model.)

To all whom it may concern:

Be it known that I, JAMES C. HURD, a citizen of the United States, residing at Springfield, in the county of Hampden and State of Massachusetts, have invented certain new and useful Improvements in Paper Boxes, of which the following is a specification.

My invention is a paper box consisting of a rectangular sheet cut and folded to form a rectangular body, and slit and bent at the ends to form a tongue and end section, with side edges turned in along the width of the section to form side flanges, and with independent side flaps the width of the side sections, the whole forming a box with flaps which will effectually close the ends, presenting flat surfaces free from creases or ridges.

In the drawings, Figure 1 is a view showing the form of blank from which the box is made; Fig. 2, a perspective view showing the blank as folded to form a rectangular tube. Figs. 3 and 4 are views showing the manner in which the end pieces or flaps are manipulated to close the ends of the box.

The blank A is a sheet of substantially rectangular form, there being at one side an offset, *a'*, which is gummed and applied to the opposite side, at *w*, after the blank is folded on the parallel lines 1 2 3 4, to form a rectangular tube, as shown in Fig. 2. The lines divide the blank into four sections, *a b c d*, the sections *a c* constituting the front and back of the folded tube, and the sections *b d* the sides thereof. The ends of the blank beyond two lines, *x y*, are divided by straight slits *t* and angular slits *s*, to form two rectangular tongues, *e e*, two sections, *ff*, with side flanges, *g g*, and four flaps, *h*, widest at the base and narrower at the ends. After the blank has been folded into a tube, the flaps *h* constitute the supplemental or inside end pieces, which are first turned down to overlap each other and partly close the end of the box, as shown in Fig. 3. The flanges *g* are then folded in toward the inner face of the section *f*, thereby forming a pocket, into which the end of the tongue *e* is introduced, as shown in Fig. 4, the tongue being then pushed farther in as the end section is carried downward until the latter is flat upon the body and the tongue wholly within the pocket. In this position the flanges *g* rest upon the inner end pieces, *h*, which pre-

vent them from turning away from beneath the tongue *e*, so that the latter is held securely. For additional security, however, the ends of the pieces *h* may be united by forming a lip, *w'*, on one and a slit, *q*, in the other, Figs. 1 and 3, the engagement of which holds the two parts together. By this construction the flaps or tongues constituting the ends of the box are very securely connected, yet so as to permit the box to be opened without injury to any of the parts, and the outer end sections are flat, free from creases or folds, so that they will receive perfect impressions in printing, and will afford proper surfaces for the attachment and exhibition of labels. They are also more slight than those in which connected flaps are exposed. Owing to the contact of the side edges of the flap *e* with the folded edges of the flanges *g*, and to the relative arrangement of flaps and tongues, a very rigid end is formed, imparting much rigidity and strength to the box.

It will be evident that it is not essential to separate the portions *h g* upon lines of any special direction, as the division may be on diagonal lines, or on lines parallel to the slits *t*, as shown in dotted lines, Fig. 1.

The tongue, when of heavy material, has a transverse crease, *v*, Fig. 3, to facilitate its introduction into the pocket.

The edges of the body portion of the box may be connected in any suitable manner.

Without limiting myself to the precise arrangement of parts described, I claim—

1. A paper box consisting of a rectangular blank formed into a rectangular tube, and slit and bent at the end to form a tongue, *e*, and end section, *f*, with side edges turned in along the width of the section to form inturned side flanges, and with independent side flaps the width of the side sections, substantially as described.

2. A paper box consisting of a substantially rectangular blank formed into a rectangular tube, and slit upon the straight line *t* and bent line *s*, to form independent tongues and flaps for infolding to close the ends, substantially as described.

3. A paper box having a rectangular body, inwardly-folded end pieces extending from the sides, and the width of the latter, an outer end piece with inturned edge flanges

extending along its entire width and independent from the side flaps, and a tongue inserted between the flanges and the end piece, substantially as described.

5 4. A box having a rectangular body prolonged at the front and back to form an end section, *f*, and a tongue, *e*, with a crease, *v*, and with side flanges on the end section of equal width therewith, and flaps independent

of the end flanges extending inward from the ro sides, substantially as described.

In testimony whereof I have signed my name to this specification in the presence of two sub-scribing witnesses.

JAMES C. HURD.
